PRESS WITH WORK EJECTOR

Walter Ernst, Mount Gilead, Ohio, assignor to
 The Hydraulic Press Corporation, Inc., Wil-
 mington, Del., a corporation of Delaware

Application March 23, 1937, Serial No. 132,574

2 Claims. (Cl. 113—50)

This invention relates to presses, and in particular, to presses having means associated therewith for ejecting work-pieces therefrom.

One object of this invention is to provide a press having means associated therewith and responsive to the return stroke of the platen for ejecting the work-piece from the die of the press.

Another object is to provide such a press, wherein a fluid-operated work-ejecting cylinder is controlled by a valve which, in turn, is actuated in response to the return stroke of the platen to eject the work-piece from the die.

Another object is to provide a press having a fluid-operated work-ejecting cylinder associated with the platen or ram of the press, and controlled by a valve which is operated automatically in response to the completion of the pressing stroke of the press.

Another object is to provide a press having a fluid-operated work-ejecting cylinder mounted upon the platen or ram of the press and controlled by a valve, which in turn, is shifted by its engagement with a member mounted to permit relative movement between the valve and the member.

Another object is to provide a press having a fluid-operated work-ejecting cylinder mounted upon the platen or ram, together with a valve which is automatically shifted on the return stroke of the platen to advance the ejecting plunger and 30 expel the work-piece, and on the forward stroke of the press is operated to retract the plunger so as to place it in readiness for expelling the next work-piece as soon as the next forward or pressing stroke is completed.

35 In the drawings:

Figure 1 is a diagrammatic view, in central vertical section, showing the principal parts of a press having one embodiment of the work-expelling means of this invention associated therewith.

40 Figure 2 is a central vertical section through the fluid-operated work-ejecting cylinder associated with the press.

Figure 3 is a bottom plan view of the work-ejecting cylinder shown in Figure 2.

45 Figure 4 is a side elevation, partly in section, of the press ram shown in Figure 1.

Figure 5 is a bottom plan view of the press ram shown in Figure 4.

In general, the invention consists of a press 50 having a fluid-operated work-ejecting cylinder associated with the ram or platen thereof. The fluid for operating this cylinder is controlled by a valve, preferably a four-way valve, which is operated by means responsive to the return stroke 55 of the platen for ejecting the work-piece.

Referring to the drawings in detail, Figure 1 shows diagrammatically the principal elements of a press having the work ejector of this invention. The press consists of a frame top member 10 and a bed 11 having a working surface 12 for supporting suitable dies, or other apparatus used in connection with the press. The top member 10 and bed 11 are ordinarily interconnected by strain rods which are here dotted in order to bring out clearly the other elements of the press. A control rod 13 also interconnects the top member 10 and the bed 11, and is mounted in the bores 14 and 15 thereof. The stop or cam member 16 is mounted for adjustable movement along the control rod 13, and may be clamped in any desired position by tightening the screw 17. The cam member or stop 16 is provided with a cam edge or surface 18 for operating a valve, in a manner hereinafter described.

The frame top member 10 is provided with a cylinder 19 having a bore 20, within which a hollow ram 21 is adapted to reciprocate. A gland 22 and a packing 23 prevent leakage of fluid between the ram 21 and the cylinder bore 20. The ram 21 is provided with a recessed head 24 and also with an interior chamber 25 having an outlet bore 26 (Figure 4) near the bottom thereof. This bore 26 widens into a larger outlet bore 27 forming an annular surface 28 between the bore 26 and the outer wall 29 of the ram 21.

30 Associated with the outer wall 29 are recesses 30 spaced at intervals around the periphery of the ram 21. Between the apertures or bores 26 and 27 is an annular recess 31. This recess 31 is provided with a plurality of threaded bolt 35 holes 32 for the attachment of the fluid-operated work-ejecting cylinder, generally designated 33. Also provided in the bottom wall 28 of the ram 21 are threaded bolt holes 34 serving for the reception of the bolts 35, by which the press 40 platen, generally designated 36, is secured to the ram 21. The press platen 36 is provided with a hollow chamber 37 therein, and likewise with a bottom or pressing surface 38 having an aperture 39 therein for the passage of a work-ejecting plunger 40. Secured to the opposite end of the plunger 40 is a piston head 41 which reciprocates in a cylinder bore 42 within the work-ejecting cylinder 33. The latter is provided with a bore 43 for the passage of the ejecting plunger 40, a packing 44 and retaining plate 45 being provided for preventing leakage around the plunger 40. The plate 45 is secured in position by means of the cap screws 46.

45 The bore 43 and the packing 44 are mounted 55

in the cylinder head 47, which is secured to the main portion 48 of the cylinder 33 by the bolts 49 (Figure 3). The cylinder head 47 is provided with a threaded port 50 for the reception of a pipe 51, by which fluid is admitted to the space beneath the piston head 41. The cylinder head 47 is likewise provided with a bore 52 through which passes a pipe 53, terminating within the threaded port 54 (Figure 2) leading 10 to the passageway 55 within the walls of the main portion 48 of the cylinder 33. At its upper end the passageway 55 terminates in a threaded port 56 having the threaded connection 57, from which the pipe 58 passes to a threaded connection 15 59 secured within the threaded port 60 in the upper wall of the main cylinder portion 48. The pipe 53, passageway 55 and pipe 58 convey fluid to the space above the piston head 41.

The cylinder portion 48 is provided with a 20 marginal flange 61 which fits within the outlet bore 27 of the plunger or ram 21. The pipes 51 and 53 pass through the hollow chamber 37 within the platen 36 by way of the opening 62 therein, and pass outwardly through an opening 63 in the top wall thereof to a valve 64. The latter is mounted upon a bracket 65 on the upper surface of the platen 36, and is provided with intake and exhaust lines 66 and 67, respectively. These lines 66 and 67 lead to any suitable source 30 of pressure fluid, such as a pump, the distribution of this fluid being effected by the valve 64. The valve 64 is preferably a four-way valve of conventional construction, and is operated by a valve lever 68 having a roller 69 mounted on the 35 upper end thereof, and adapted to be operated by engagement with the cam surface 18 of the cam or stop 16 as the platen 36 and ram 21 execute the various strokes of the press.

In the operation of the press and work ejector 40 of this invention, the press is started upon its forward stroke by admitting pressure fluid to the space above the main ram 21. Preferably a surge valve system (not shown) is employed to permit the ram 21 to coast downwardly under 45 the influence of gravity, and thereby approach the work more rapidly. As the platen 36 moves downwardly the lever 68 of the valve 64 passes the cam 16 so that the roller 69 engages the cam surface 18 to move the valve lever 68 counterclockwise. This action admits pressure fluid 50 into the space beneath the ejector piston head 41, thereby insuring that the ejector plunger 40 will be in its retracted position at the time the platen 36 and its die engage the work.

55 After the platen and the die or dies have completed the pressing stroke, the platen 36 begins its return stroke by the action of the usual return or push-back cylinders (not shown). As the valve 64 again passes the cam 16 on the 60 return stroke of the platen 36, the roller 69 again engages the cam surface 18, swinging the valve lever 68 in a clockwise direction. This shifts the valve 64 to admit pressure fluid into the space above the ejector piston head 41, causing the ejector plunger 40 to move downwardly 65 and eject the work-piece from the die. The length of the cam surface 18 determines the length of time during which pressure fluid will be applied to the ejecting cylinder 33, after 70 which the valve roller 69 slips off the cam surface 18 and causes the valve lever 68 to return to its

neutral position, wherein the fluid is completely shut off.

After the platen returns to its top or retracted position, the ejector plunger 40 will, of course, be in its advanced or ejecting position, but will be again retracted when the valve 64 is again shifted by the engagement of the valve roller 69 with the cam surface 18 upon the next forward stroke of the platen 36. The details of the four-way valve 64 form no part of the present invention as this valve is of any suitable conventional design. It is evident that in the operation of the four-way valve 64, when the pressure line 66 is connected through the valve 64 to one side of the ejector piston head 41, the exhaust line 67 is automatically connected through the valve 64 to the space on the opposite side thereof.

The ejector plunger 40 and its piston head 41 may be operated by any suitable fluid, compressed air having been found convenient for this purpose. It will be obvious, moreover, that the application of this work-ejecting device is not confined to fluid-operated presses, but may be employed equally well with mechanically-operated presses.

It will be understood that I desire to comprehend within my invention such modifications as come within the scope of the claims and the invention.

Having thus fully described my invention, what I claim as new and desire to secure by Letters Patent, is:

1. In combination in a press, a main cylinder, a main plunger structure reciprocable relatively to said main cylinder and operated thereby, a double-acting work-ejecting cylinder and piston mounted on said plunger structure and movable therewith, a work ejector connected to said piston, an ejection control valve mounted on said structure and having a valve-operating member connected thereto, a stationary support mounted adjacent said plunger structure, and a valve-actuating cam adjustably mounted on said support and disposed in the path of travel of said valve-operating member, said valve-operating member being engageable with said cam to shift said valve at predetermined positions upon the forward and return strokes of said plunger structure to respectively retract and advance said work ejector.

2. In combination in a press, a main cylinder, a main plunger structure reciprocable relatively to said main cylinder and operated thereby, a double-acting work-ejecting cylinder and piston mounted on said plunger structure and movable therewith, a work ejector connected to said piston, an ejection control valve mounted on said structure and having a valve-operating member connected thereto, a stationary support mounted adjacent said plunger structure, and a valve-actuating cam adjustably mounted on said support and disposed in the path of travel of said valve-operating member, said valve-operating member being engageable with said cam to shift said valve at predetermined positions upon the forward and return strokes of said plunger structure to respectively retract and advance said work ejector, said main plunger structure being hollow and said work-ejecting cylinder and piston being mounted in the interior of said hollow plunger structure.

WALTER ERNST.
